DOUBLE REGENERATIVE REPEATER

Louis M. Potts, Evanston, Ill., assignor to Teletype Corporation, Chicago, Ill., a corporation of Delaware

Original application January 18, 1941, Serial No. 374,991. Divided and this application November 2, 1942, Serial No. 464,214

12 Claims. (Cl. 178—70)

This invention relates to printing telegraph systems and more particularly to regenerative telegraph signal repeaters therefor.

This application is a division of application Serial No. 374,991, filed January 18, 1941, now Patent No. 2,339,804, granted Jan. 25, 1944.

The primary object of the present invention is to provide a double regenerative repeater for automatically producing two definitely spaced signal impulses for each received signal impulse.

Another object of the invention is to provide a regenerative repeater having means to generate a first set of signals corresponding to signals received by said repeater and means to generate a second set of signals identical with but lagging by a predetermined time interval said first set of regenerated signals.

More specifically, the present invention contemplates the combination of structures heretofore separately identified as regenerative repeaters and storing repeaters into a single unitary mechanism. Means is also provided for maintaining the delay inserted in the transmission system at a given value for the duration of the transmission of an integral number of complete signal combinations. Briefly, the device for achieving the objects of the present invention comprises a mechanical repeater of the type shown in United States Patent No. 2,105,173, modified so as to generate two signal impulses in response to each received signal impulse.

A more complete understanding of the invention may be had from the following description taken in connection with the accompanying drawings wherein,

Fig. 1 is an elevational view of the repeater mechanism according to the present invention;

Fig. 2 is a sectional view taken on line 2—2 of Fig. 3;

Fig. 3 is a side elevational view of said repeater mechanism;

Fig. 4 is a detailed view of the armature, taken on line 4—4 of Fig. 1;

Fig. 5 is a detailed view of the cam sleeves;

Fig. 6 is a perspective view partly exploded of the repeater according to the invention;

Fig. 7 is a timing diagram of one mode of operation of the repeater illustrated in Figs. 1 to 6, inclusive; and

Fig. 8 shows telegraph stations interconnected to a central office, which circuit arrangement embodies the combination repeater mechanism of the present invention.

Illustrated in Figs. 1 to 6, inclusive, is a mechanical regenerative repeater of the form shown

and described in United States Patent No. 2,105,173, issued to W. J. Zenner et al., the structure of the Zenner et al. patent being modified for the purposes of the present invention to generate two signal impulses at the repeater in response to each received signal impulse, the two regenerated signal impulses being similar in nature but displaced in time from one another. Accordingly, the disclosure of the noted Zenner et al. patent is made a part of this application and will be referred to further herein.

Referring to Figs. 1 to 6, inclusive, there is shown mounted rigidly on a frame plate 10 a pivot stud 11 upon which there oscillate independently an armature member 12 and first and second repeating members 25 and 35, respectively.

The repeater magnet 13 is provided with an armature 12 of yoke form and pivotally mounted on stud 11 by yoke arms 14 and 15 (see Fig. 3). The armature comprises a plurality of extensions, namely, portion 16 which is attracted directly by the magnet, a first cam follower 17 and a second cam follower 18 passing through an opening 23 (see Fig. 4) in frame plate 10 and these followers are controlled by cams 85 and 86, respectively, for mechanically assisting armature 12, a starter striker 19 on an arm 33 to initiate the operation of the repeating mechanism, a latch lever 20 which is a subextension on cam follower 18 and which determines the delay inserted in the transmission circuit, and a pair of anchor arms 21 and 22 to which springs extend and provide a self centering mechanism 35 for repeater tongue 25 with respect to the armature 12.

The regenerative repeater member 25 also pivotally supported by the stud member 11, engages the stud member by yoke arms 24 positioned between the yoke arms 14 and 15. It is provided with a plurality of operating extensions; namely, a pair of signal repeating electrical contacts 26 to transmit the regenerated signal impulses, a pair of transfer abutments 29 and 30 on a lateral arm 27 passing through an opening 28 in frame plate 10 to control regenerative repeater member 35, a lock edge 31 and a jockey edge 32 to hold repeater member 25 in its various positions (see Figs. 2, 4, and 6).

A storage repeater member 35 also is pivotally supported by the stud member 11, engaging the stud 11 by yoke arms 36 and 37 on alternate sides of plate 10 and connected through the web body of the member 35, passing through an opening 55 in the frame plate 10. In front of the frame 10,

the web body of the member 35 carries an integral extension 38 provided with a pair of electrical contacts 39 which engage one or the other pair of two pairs of anvil contact points 40 (see Fig. 1). At the back of the frame plate 10, the member 35 is provided with an arm 41 extending from the yoke arm 37 and having a bifurcated end (see Figs. 2 and 6).

Cooperating with the two repeater members 25 and 35 is a transfer assembly for controlling repeater member 35 to cause it to regenerate and repeat signal impulses and it comprises a transfer lever (see Figs. 1, 2, 3, and 6) 42 pivoted on a fixed post 43 and provided with a cam follower 44 and with an extension arm 45 which carries at its distal end a pivot pin 46. The pivot pin 46 carries a transfer T 47 which upon being moved by the arm 45 under power from cam follower 44 may engage alternatively either the abutment 29 or the abutment 30 on extension arm 27 of repeater member 25 and be rotated upon its supporting pin 46.

The particular abutment with which T 47 engages is determined by the position of repeater member 25. That is, if repeater member 25 is in its lower position repeating a spacing impulse, abutment 29 on extension 27 of member 25 is in alignment with and will be engaged by T 47, whereas, when a marking impulse is being repeated by member 25, that member is in its upper position and T 47 will engage abutment 30 (see Fig. 2). Transfer T 47 carries a transfer pin 48 which at all times is confined within the bifurcation of the arm 41 of storage member 35 and which acts to shift the member 35 oscillating upon its supporting stud 11 in response to the shifting of T 47 about its pivot 46.

A continuously driven power shaft 50 is provided as shown in the Zenner et al. patent referred to above. This shaft carries a first cam sleeve 51 and a second cam sleeve 52 (see Fig. 5). The need for a plurality of cam sleeves will be apparent from the description of the operation of the regenerative apparatus. Friction plates 53 and 54 are fixed to shaft 50 while shouldered friction plates 55 and 56 are slidably carried by shaft 50, the shoulders of the plates being splined together and the assembled plates 55, 56 being splined to the shaft by a screw 58 the tip of which enters a keyway (not shown) in shaft 50. Friction rings 60 are provided between the described friction plates and the described cam sleeves. A single compression spring 61 keeps all friction members under pressure.

Cam sleeve 51 is held latched by latching mechanism provided as shown in the Zenner et al. patent but not reproduced here and is released by armature 16 and starting striker 19. Cam sleeve 52 is held latched by a latch arm 10 when the arm is in engagement with a tooth on cam 67 (see Figs. 2, 3, and 5). A rocker shaft 68, journaled in the frame plate 10, carries fixed upon it at one end the cam follower 69 which follows the cam 66 on the first cam sleeve 51 in front of the frame plate 10, and carries fixed upon it at the other end the latch arm 10 which engages the cam 67 on the second cam sleeve 52 at the back of the frame plate 10.

A latch lever 79 for repeater 25 has the form of an extension arm on a latch lever member 81 of yoke form extending on either side of plate 10, the two yoke arms of which are pivotally supported at the two ends of a stud member 80 fixed in the frame member 10. An extension arm 76 of lever 81 terminates in a cam follower for the

release cam 75 on the first cam sleeve 51 and is operated by the cam 75 to operate the lock lever 79 in the manner illustrated and described in the patent to Zenner et al. A further extension arm 78 at the opposite end of lever 81 terminates in a cam follower for the release cam 77 on the second cam sleeve 52 (see Figs. 1, 3, and 6). A spring 49 urges lever 81 counterclockwise, retaining its follower projections against these cams.

Springs 82 and 83 approximately alike in all dimensions, extend respectively from anchor arms 21 and 22 on the armature member 12 to regenerative repeater member 25, providing a self-centering articulation. A jockey 97 pivoted at 98 is retained by spring 99 against the described jockey edge 32 on the repeater member 25 (see Figs. 1 and 3).

Cam sleeve 52 carries a cam 84 for the described cam follower 44 of the transfer assembly 42. Cam sleeve 51 carries a cam 85 for follower 17 and cam sleeve 52 carries a cam 86 for follower 18, both followers 17 and 18 being integral with armature member 12 as described above.

Means is also provided for maintaining the delay inserted in the transmission system at a given value for the duration of the transmission of an integral number of complete signal combinations. Cam sleeve 52 carries a cam 87 (see Figs. 2 and 3) for a cam follower 89 integral with a lever 88 of yoke form pivotally supported upon a fixed stud 90 carried by plate 10 one arm of the yoke passing through an opening 96 (see Fig. 1) in the frame plate 10 and being provided with the said integral cam follower 89 and with a notched locking extension 92. A rocking latch 93 pivoted upon a fixed pivot 94 may engage the notch in the extension 92 as illustrated in Figs. 2 and 6 and may be rocked out of latching position by the operation of the described striker 20 (see Figs. 3 and 6) on armature member 12 upon the receipt of the starting impulse.

Reference to Fig. 7, wherein there is illustrated a timing chart for one particular embodiment of the combined repeater mechanism, will demonstrate the necessity for a plurality of cam sleeves and render the subsequent description of the operation of the apparatus more easily understandable.

In Fig. 7, A represents a start-stop code signal received by magnet 13, the start impulse of which releases first cam sleeve 51;

B represents the operation of cam 66 and shows at b the release of second cam sleeve 52 one half a signal impulse period after the release of first cam sleeve 51;

C represents the actuation of release cam 75 permitting the position of repeater member 25 to correspond to the position already assumed by armature 12 and at c there is indicated the release of repeater member 25 one half an impulse period after the reception of the start impulse, interposing a delay of one half a signal impulse period between the received signal combination and the signal repeated by the first regenerative repeater unit;

D represents the cycle of transfer cam 84 and demonstrates at d the transfer of the first, or start, impulse through the transfer mechanism to the second, or storage, regenerative repeater member 35 at a full impulse period after the received start impulse; that is, when the No. 1 signal impulse reaches the repeater magnet, the start impulse is being transferred to the second regenerative repeater 35;

E illustrates the operation of cam 85 to assist

the operation of the armature 12 and e indicates the operation of follower 17 by this cam so that the armature is under the control of the No. 1 received impulse;

F discloses the operation of release cam 77 which is similar to that of release cam 75 in point of time but shows the releasing mechanism to be under the control of a cam on sleeve 52 for all signal impulses except the start impulse;

G is a diagram of the cycle of cam 86 for providing assisted armature operation and the cam is actuated in a manner similar to that of cam E except that cam 86 is for those impulses exclusive of the first impulse;

H and I represent the signals repeated by regenerative repeaters 25 and 35, respectively, and show the delay of one half a signal impulse period in signals transmitted by repeater 25 and a delay of a full signal impulse period in the signals transmitted by repeater 35;

J represents the operation of cam 87 to return the control to magnet 105 when storage repeater 35 is transmitting the stop impulse.

A study and comparison of curves A, B and D will reveal that the transfer of the stop impulse from the transfer mechanism to repeater 35 takes place at d1 at which time the original stop impulse has been fully received by magnet 13 and first cam sleeve 51 is at rest. Hence, if transfer cam 84 were carried by first cam sleeve 51, the stop impulse would not be transferred to repeater 35 and for that reason a second cam sleeve 52 is provided to accommodate the transfer cam 84.

At g5 is indicated one time at which the armature 12 is mechanically translated to its attracted position to afford assisted armature action and it is there clearly illustrated that this is very near the time at which first cam sleeve 51 is arrested, having completed one cycle. Similarly, at f6 there is represented the time at which repeater member 25 is released to be positioned to transmit the stop impulse and this, too, occurs at nearly the time when the first cam sleeve 51 is arrested. Although it is possible to arrange cams 85 and 75 to perform all the armature assisting and releasing operations respectively, the present embodiment of the invention contemplates dividing these operations, as disclosed, between cams 85, 86, and cams 75, 77. Since the second cam sleeve 52 is necessary as above shown, the additional cams 86 and 77 are also mounted thereon to permit more facile orientation and assure the required time relationships. The particular allocation of operations between cams 85, 86, and cams 75, 77, is not important, and, if desired, cam 86 may be a one tooth cam, as may cam 77. The cams 86 and 77 are provided in order to provide for more certain time relationships at the times indicated at g5 and f6, respectively.

In the modifications shown in the above-mentioned patent there was illustrated a cam switch at each regenerative repeater, provided to assure that the delay inserted in the transmission circuit be maintained during the transmission of an integral number of complete signal combinations to prevent signal mutilation. Means is provided in the present modification to give the same assurance and it comprises contacts 101, 102, and 103, controlled by armature 104 of magnet 105 (see Figs. 1, 6 and 8). Armature 104 has connected communication line 114 to storage repeater 35 introducing a delay of a full signal impulse in the transmission circuit. With armature 104 attracted, line 114 is connected to re-

generative repeater 25 with a delay of half a signal impulse in the circuit. The locking edge 91 of member 88 operates under the control of cam 87 to maintain armature 104 in the condition existent upon the receipt of the start impulse for the transmission of one entire signal combination. Curve J demonstrates that the locking edge 91 is not operated to release armature 104 until after the transfer of the stop impulse to repeater 35, at which time first cam sleeve 51 has been arrested and, therefore, second cam sleeve 52 is necessary to provide a release for armature 104 after a signal combination has been fully repeated by repeater 35 as well as repeater 25.

Having reference to Fig. 8, the combination repeater mechanism disclosed in Figs. 1 to 6, is shown connected in a circuit comprising a plurality of substations and a central station. At 120 is represented the central office through which the substations 111 and 113 are connected for intercommunication. A transmitting distributor 121 is located at the central office and is driven from a speed controlled motor 128 through gearing 129. The distributor includes a shaft 122 carrying cams 123, 124, and 127 operative to establish and maintain synchronous operation over main channel C in a manner described in the parent application Serial No. 374,991 previously referred to. Substation 111 and combination repeater 112 are connected over conductor 114 to central office 120, and substation 113 and combination repeater 115 are connected over conductor 116 to the central office. Substation 111 includes a transmitter 117 (which may be tape controlled or a direct keyboard type), a home recorder 118, and a receiving recorder 119. Other substations, for example, 113 included in the circuit arrangement are similar.

In general, conductors 114 and 116 form a part of branch circuits A and B, respectively. Branch circuit A is termed a "basic" circuit because it is normally conditioned for simplex operation. Reference to Fig. 8 will show that conductor 114 is normally connected directly to conductor 130 of main channel C through the contacts 131 at relay 132 completing a simplex communication path from a substation 111 to main channel C. Main channel C is shown as part of a carrier telegraph system including a carrier conductor 133 to which the basic circuit is extended over conductor 130 and, therefore, it is proper to call conductor 130 an extension conductor to which basic circuit A is normally connected.

Branch circuit B is termed an "additive" circuit because it is normally out of the telegraph system but may be added thereto. Conductor 116 of circuit B, for example, is normally interrupted at the outer right-hand armature of relay 132 and, when relay 132 is energized, circuit B is added to extension conductor 130 in alternation with basic channel 114 through the distributor 121 and its cam controlled contacts.

As described in the parent application, to initiate the operation of additive circuit B and thus establish the alternate condition, manual key 134 is closed momentarily to energize relays 135 and 136 over an obvious circuit. Relay 135 closes its holding contact to form an obvious holding circuit for relays 135 and 136. Relay 136 operates and connects power conductors 137 to the motor 128 thus placing the motor 128 in operation to drive the distributor shaft 122.

There is provided at central station 20 a plurality of relays, such as 161, one of which is as-

sociated with each extension conductor and which must be operated to convert the extension conductor from simplex to multiplex operation. The circuit for these relays is closed by slow-to-operate relay 160 when motor 128 has attained a predetermined speed, as described in the parent application, Serial No. 374,991, filed January 18, 1941. Since relay 160 is slow-to-operate, it will not actuate until the motor 128 attains and holds its synchronous speed. When relay 160 operates, the circuit including relay 161 and others (not shown) for the remaining communication channels of the system, is completed, thus operating relay 161 preparatory to connecting basic circuit A and additive circuit B to extension conductor 130 through cam controlled contacts 150 and 154. When relay 161 operates, armatures 140 and 141 are attracted, thus closing their associated contacts.

The system shown in Fig. 8 has a normal and an alternate condition, the former of which will now be described. Referring to Fig. 8, it will be presumed that the mechanical distributor 121 is not operating and that substation 111 is not transmitting, the entire system being mechanically inert but being in a condition of electrical preparedness. Magnet 13 is held energized by current in a circuit through the transmitter at substation 111. Magnet 105 is de-energized because its circuit including contacts 138, conductor 139, right-hand winding of relay 132, armature 140, line 142, contacts 143 at cam 124, line 144, and ground is open at armature 140. Magnet 146 is held energized by current in a circuit including conductor 147, contacts 148 and conductor 149 to ground.

Upon generation of a permutation code signal at substation 111, magnet 13 is de-energized at the beginning of the start impulse. Armature 16 (see Fig. 1) is released and striker 19 (Fig. 3) releases the first cam sleeve 51 as described in the Zenner et al. patent. Release of armature 16 also operates armature member 12 clockwise under the force of spring 34 and striker 20 which engages and rocks the latch 93 (Fig. 6) to release the locking member 88 which, urged by the tension of spring 95, engages the armature 104, preventing the shifting of the contact spring 101 during the period of transmission of the then ensuing code signal. Because of the movement of armature member 12, one of the springs 83 now tensions the repeater member 25 against the latch 79.

After a delay of one-half signal impulse time period, cam 75 operates the follower 76 and latch 79 as described in the Zenner et al. patent, and the cam 66 operates the follower 69 to rock the shaft 68 and latch 70, thus releasing the second cam sleeve 52 with a delay of one-half signal impulse time period after the release of the first cam sleeve 51. Latch 79 momentarily releases the repeater member 25 which shifts its abutments 29, 30 and also operates its electrical contacts 26 thus repeating the starting signal impulse into the contacts 26 with a time delay of one-half signal impulse period as compared with the original signal impulse.

After a further delay of approximately one-half signal impulse time period from the instant of operation of the contacts 26, and just preceding the beginning of the No. 1 character code impulse of the permutation code signal, presumed to be an impulse of marking signal nature, cam 84 operates its follower 44 which propels the T 47 against the shifted abutment 29 and by the re-

sultant rocking of the T 47 effects a shifting of arm 41 and storage member 35 to repeat the starting signal impulse into the contacts 29 with a time delay of one full signal impulse period as compared with the original signal impulse.

The first impulse is then received, energizing magnet 13 but with the holding type magnet employed, the magnet is not strong enough to attract its armature. After the No. 1 impulse has been sustained for nearly half a signal impulse period, cam 85 operates its follower 17 to restore armature member 12 to its attracted position as described in the Zenner et al. patent, thus causing spring 82 to tension repeater member 25 for a marking signal impulse. Since a marking impulse is being received, magnet 13 now retains armature 12 in its attracted position. The employment of a holding magnet of this nature enables the multiplex to be conditioned by only a part of the received signals and consequently, limited mutilation of the received signals is eliminated and not transferred into the multiplex system.

At an instant one-half signal impulse time period after the beginning of the No. 1 impulse in magnet 13, cam 77 operates its follower 78 and latch 79 to momentarily release the repeater member 25 which is then shifted by spring 82 to repeat the marking impulse into contacts 26 and to shift abutments 29 and 30. At an instant approximately one full signal impulse time period after the beginning of the No. 1 impulse in magnet 13, cam 84 operates its follower 44 and propels the transfer T 47 against restored abutment 30 to operate the storage repeater member 35 and to repeat the No. 1 signal impulse into the contacts 39 with a delay of one full signal impulse time period after the beginning of the No. 1 signal impulse in magnet 13. In like manner the remaining impulses of the signal combination are repeated at contacts 26 and 39.

During the time period of the stop impulse of the received code signal the first cam sleeve 51 is stopped by stop arm 74 as described in the Zenner et al. patent and one-half signal impulse period later the second cam sleeve 52 is stopped by engagement of cam tooth 67 with latch arm 70. Just before the second cam sleeve 52 stops, cam 87 engages its follower 89 and shifts the locking member 88 into position to release the armature 104 in which position the locking member 88 is engaged by locking latch 92 and is restrained pending receipt of a starting impulse by the magnet 13. All apparatus is again at rest.

During the receipt and retransmission of each successive code signal, the signal impulses are repeated into contacts 26 with a delay of one-half impulse period and also are repeated into contacts 39 with a delay of one full impulse period. The position of contact spring 101 determines whether the basic circuit 114 shall be connected to contacts 26 for retransmission with a delay of one-half impulse period or to contacts 39 for retransmission with a delay of one full impulse period. The position of contact spring 101 is determined by the position of armature 104 at the instant that the locking member 88 is unlatched by the armature 16 acting through striker 20 and latch 93 in response to a received starting impulse of a code signal combination.

In the normal condition of the particular embodiment of the invention under consideration, magnet 105 is de-energized, as illustrated in Fig. 4 and accordingly, line 114 is connected to storage

repeater 35 and there is a full signal impulse period delay inserted in the circuit.

The alternate condition of the system, wherein the basic and additive circuits are operative, will now be considered and it will be assumed that the system is conditioned for synchronous multiplex telegraphy.

When additive circuits are being used, the distributor 121 rotates continuously and magnets 105, 146, receive impulses of current in uninterrupted sequence from contacts 143, 148, of cam 124.

The signal impulses for the basic circuit are transmitted through contacts 150 (see Fig. 8). Should the beginning of the start impulse in magnet 13 occur with distributor 121 operating and with the distributor cams 123 and 124 transiently in the position shown with contacts 150 closed and contacts 143 open, conductor 142 would be open at contact 143 of cam 124, magnet 105 would be de-energized and contact 101 would be in engagement with contact 103, as shown, connecting conductor 114 to contacts 39 of storage regenerative repeater 35. At a half impulse period later, the contact 150 will be found open and the starting impulse will be transmitted into contacts 151 ineffectively. At a further half impulse period later the contact 150 will be found closed and the starting impulse will be transmitted into contacts 152, thence through contacts 103, 101, conductor 114, contacts of operated relay 132, contact 150 and extension conductor 130 to line transmitting relay 153. Upon the receipt of the start impulse, locking lever 88 operates and holds armature 104 immobile during the ensuing signal combination.

Should the beginning of the start impulse in magnet 13 occur with distributor 121 operating and with the distributor cam 123 transiently in its position alternative to that shown, with contacts 150 open, conductor 142 would be closed at contact 143, magnet 105 would be energized and contact 101 would be in engagement with contact 102 connecting line conductor 114 to the regenerative repeater 25. At a half impulse period later, the contact 150 will be found closed and the starting impulse will be transmitted into contacts 26 thence through contacts 102, 101, conductor 114, contacts of operated relay 132, contact 150 and extension conductor 130 to line transmitting relay 153. Signal impulses will be repeated into contacts 39 but without effect since they are disconnected from the line. The operation of combination repeater 115 is identical with operation of repeater 112, transmission being over conductor 116 of the additive circuit and contacts 154 of cam 123 to relay 153.

At the end of each revolution of second cam sleeve 52 the cam 87 engages its follower 89 and operates the locking member 88, withdrawing the locking edge 91 from engagement with armature 104, permitting the armature 104 to respond to magnet 105 according to the energized or unenergized condition of the magnet 105. The contact spring 101 thus may be readjusted invariably by the transmitting phasing cam 124 between successive code signals even though the successive code signals are continuous as would be the condition with a tape controlled transmitter operating at station 111.

Locking lever 88 carries two contact operating devices, shown diagrammatically in Fig. 8, for operating contacts 138 and 155 to prevent signal multilation by converting to multiplex operation during the transmission of a signal combination

over the basic circuit. That is, upon the receipt of a start impulse by magnet 13, latch 93 is rocked and lever 88 rotates counterclockwise under the influence of spring 95 disengaging contacts 138 and 155. Should key 134 be depressed at this time, the establishment of multiplex operation would be delayed because the circuits to the energizing windings of relay 132 are disabled at contacts 138 and 155. Upon the receipt of the stop impulse, member 88 is rotated clockwise by cam 87 and closes contacts 138 and 155 permitting relay 132 to be energized over the circuit including battery, magnet 105, contacts 138, line 139 and right-hand winding of relay 132 or the circuit including battery, contacts 155, line 156 and center winding of relay 132. From relay 132, each circuit is completed through contact 143, line 144 and ground. Accordingly, conditioning the system for the multiplex operation may be accomplished without interrupting transmission over the basic circuit.

When the system is conditioned for multiplex operation and one of the branches, say line 114, is idle, the transmitting phasing cam 124 through contact 143, lines 142 and 139 alternately energizes and de-energizes magnet 105, vibrating armature 104 and connecting line 114 alternately to repeater contacts 26 and 39 in phase relation with the operation of contacts 150. Consequently, when the multiplex condition is once established, it is maintained and no matter when transmission is resumed on line 114, it will be properly phased with respect to the operation of regularly operated contacts 150.

35. What is claimed is:

1. In a repeater, means in said repeater to generate a first set of signals corresponding to signals received by said repeater, means in said repeater to generate a second set of signals identical with but lagging by a predetermined time interval said first set of regenerated signals, and means cooperating with said repeater to transmit either one of said sets of regenerated signals. 40

2. A telegraph repeater capable of generating two signal impulses for each received signal impulse comprising a magnet for receiving signal impulses, an armature positioned in accordance with the operation of said magnet, a first set of output contacts, mechanism operable after said magnet has positioned its armature to operate said first set of output contacts to generate a first signal corresponding to a received signal, a second set of output contacts, and further mechanisms operable after the operation of said first 50 mechanism and under the control of said first set of output contacts to operate said second set of output contacts to generate a second signal corresponding to said received signal.

3. In a communication system, a telegraph circuit, a start-stop repeater, means in said repeater to generate a first set of signals under the control of incoming signals, means controlled by said signal generating means to generate a second set of signals like the first but shifted in phase, means to connect one or the other of said sets of signals to said telegraph circuit, and means to operate said last mentioned means only when said first signal generating means are inoperative.

4. In a telegraph system, a transmitter, a repeater, a telegraph circuit including said transmitter and said repeater, means in said repeater to generate one set of signals in response to signals emitted by said transmitter, means in said repeater to generate a second set of signals like

the first set but shifted in phase, and means operating in phase with signals emitted by said transmitter to connect one or the other of said generating means to said telegraph circuit.

5. The method of repeating from a random timed signal source to an independently timed output which comprises the steps of generating two sets of signals from the source but differing in phase, and selecting that set for controlling the output which bears a suitable time relation to the outgoing timed source so as to pass the signals without mutilation.

6. The method of repeating from a random timed signal source of a periodically timed repeater which comprises generating a plurality of sets of signals under control of the random signals, each set having a different phase, and selecting the set which has the most suitable phase for transmission on the periodically timed signal generator.

7. In a regenerative repeater, means for generating random timed signals, an independently timed outgoing circuit, timing means in said circuit, means for repeating from said random timed signal generating means to said independently timed outgoing circuit, means to generate under control of each random timed signal two corresponding signals, means to invariably maintain a fixed lag between said two corresponding signals, and means to select one of said two corresponding signals to control transmission on the independently timed outgoing circuit according to the time of arrival of the random timed signal with respect to the phase of said timing means.

8. In a regenerative repeater, means for generating random timed signals comprising permutation code combinations of signaling impulses, a synchronous multiplex circuit, means for repeating from said random timed signal generating means to a channel of said multiplex circuit, means to generate under control of each random timed signal two corresponding signals, and means to invariably maintain a fixed lag of less than an elemental code impulse interval between said two corresponding signals.

9. In a regenerative repeater, means for gen-

erating random timed signals comprising permutation code combinations of signaling impulses, an independently timed output circuit, means for repeating from said random timed signal generating means to said independently timed output circuit, means to generate under control of each random timed signal two corresponding signals, means to invariably maintain a fixed lag between said two corresponding signals, means effective at the beginning of a code signal to select one of said two corresponding signals to control the signal on the independently timed output circuit, and means to maintain said selection until the repeating of said code signal is completed.

10. In a regenerative repeater for a multiplex start-stop extension circuit system comprising means for generating random timed start-stop permutation code signals, an independently timed outgoing circuit, transmitting means in said circuit, means to generate a plurality of sets of start-stop permutation code signals similar to the random timed start-stop permutation code signals, and means to cause one of said sets of start-stop permutation code signals to lag behind the other, whereby at least one of said sets of signals is invariably in a suitable phase for said transmitting means to pick up those signals without mutilation.

11. The method of repeating from a signal source to an outgoing circuit which comprises the steps of generating a plurality of similar signals under control of a single signal from said source, varying the phase of each of said similar signals, and selecting one of said similar signals for transmission on the outgoing circuit.

12. The method of repeating from a permutation code signal source to an outgoing circuit which comprises the steps of generating a plurality of similar permutation code signals under control of a single permutation code signal from said source, varying the phase of each of said similar permutation code signals, selecting one of said similar signals for transmission on said outgoing circuit, and maintaining the same selection during an entire permutation code time interval.
